By His Attorney B. Pickering

UNITED STATES PATENT OFFICE.

CHARLES H. CHAPPEL, OF DAYTON, OHIO.

GLUING-MACHINE FOR BINDING-STRIPS.

SPECIFICATION forming part of Letters Patent No. 395,692, dated January 8, 1889.

Application filed September 20, 1888, Serial No. 285,876. (No model.)

To all whom it may concern:

Be it known that I, CHARLES H. CHAPPEL, a citizen of the United States, residing at Dayton, in the county of Montgomery and State of Ohio, have invented certain new and useful Improvements in Gluing-Machines for Binding-Strips; and I do hereby declare that the following is a full, clear, and exact description of the invention, which will enable others skilled in the art to which it appertains to make and use the same, reference being had to the accompanying drawings, and to the letters and figures of reference marked thereon, which form a part of this specification.

15 My invention relates to improvements in a gluing-machine for binding-strips, the several features of which will be fully hereinafter set forth.

The use of my invention is to glue the under surface of a strip of paper used as a binding on the back of writing-tablets.

The object is to glue the surface while the strip is being drawn in position to be pressed down by the hands on the back of the tablet, and thereby unite the several sheets forming the said tablet.

I attain the object by the mechanism illustrated in the accompanying drawings, in which—

30 Figure 1 is a side view of the gluing-machine with portions cut away to exhibit the interior. Fig. 2 is a top view of the same. Fig. 3 is an enlarged view of one of the roller-guides. Fig. 4 is an enlarged view of the 35 scraper.

Like letters designate like parts throughout the several views.

A is a table supported on suitable legs. Near the left end is attached an ordinary 40 clamp consisting of the fixed part H and the movable part H' and having the eccentric I to operate the movable part. On the right end is attached the slotted upright L, in the upper end of which is held the roller D and in the lower end the spool E on suitable pivots. To a pin in the center of the said upright is attached the strap m, and to the end of which is secured a small weight, n, the use being to give friction to the said spool. Near the center of the table is provided a square orifice, into which is set the flanged metallic vessel C, used to hold water, and it has an under part, C',

which is open and in the bottom of which is attached the gas-burner S, the same having the flexible pipe t to convey the gas to it. Within 55 the water-compartment are lugs that serve to support the glue-vessel B. This vessel has bearings in its sides for the roller G, and ears x, attached to the ends, which form bearings for the guide-rollers u u', which are identical 60 in construction, and are clearly shown at Fig. 3. The shaft has bearings in the ears x x, with collars 1 1 outside of said ears, and the adjustable collars 2 2 serve to guide the strip of paper. The scraper w is supported at the 65 right end of the glue-vessel, and is held in longitudinal position by the screw y, which engages a nut attached to the end of said vessel. The projections on the sides of the scraper cover the sides of the roller, and the 70 end is adjusted so near that only a thin stratum of glue can be carried on the upper surface of the roller. The gas-burner heats the water and the water gives a uniform heat to the glue.

75 The paper strip F is prepared in rolls of the proper width, and is put into the spool by removing one side of the same. It is then placed in the upright L and held by a pin for its pivot. From the spool the paper is carried 80 over the roller D, under guide-roller u', over roller G, and under guide-roller u. J are the leaves for forming the tablet as they are held in the clamp in readiness to have the binding for the back applied.

85 The operation is thus briefly described. The paper strip is caught and carried over the incomplete tablet held in the clamp, the paper receiving a covering of glue on its under surface from the roller. The same is pressed down over the back and sides, thus completing the tablet.

Having fully described my invention, what I claim, and desire to secure by Letters Patent, is—

1. In a machine for gluing writing-tablets, the combination of spool E, roller D, vessel B, guide-roller u', glue-roller G, provided with scraper w, and the guide-roller u, substantially as set forth.
2. In a machine for gluing writing-tablets, the combination of spool E, roller D, vessel B, guide-roller u', glue-roller G, guide-roller u, and the clamp held on the table in central

line with the other parts, substantially as set forth.

3. The combination of the flanged vessel C, provided with compartment for the gas-burner S, the vessel B, with glue-roller G, and guide-rollers u u' , substantially as shown and described.

In testimony that I claim the foregoing as my own I affix my signature in presence of two witnesses.

CHARLES H. CHAPPEL.

Witnesses:

B. PICKERING,

SUMNER T. SMITH.
